UNITED STATES PATENT OFFICE.

WILLIAM J. RHOADS, OF CHESTER, PENNSYLVANIA.

MAIL-BAG-TRANSFER DEVICE.

1,244,372.

Specification of Letters Patent.

Patented Oct. 23, 1917.

Application filed April 21, 1916. Serial No. 92,696.

To all whom it may concern:

Be it known that I, WILLIAM J. RHOADS, a citizen of the United States, residing in Chester, Delaware county, State of Pennsylvania, have invented a Mail-Bag-Transfer Device, of which the following is a specification.

One object of my invention is to provide a relatively simple, reliable and convenient device for transferring a mail pouch from a moving car to a relatively stationary receiving device, the invention contemplating an arrangement of parts which shall be applicable to apparatus now in use with a minimum of expense and inconvenience.

I further desire to provide a novel form of mail bag holder particularly adapted for use in the door of a mail car and which, while being capable of projection outside of said car when a mail bag is to be delivered therefrom, may be easily removed or if desired swung completely into said car so as to permit of the easy placing of the bag on its arms ready for delivery.

It is also desired to provide a mail bag delivery device which shall include two arms designed to be rotatably mounted in the door of a mail car and so arranged that one of them may be easily removed or detached when not required for use; the construction being such as to permit of the car door being closed when desired.

Another object of my invention is to provide a novel device for satisfactorily receiving a mail bag from a delivery device on a moving car, which, in addition to being simple and substantial in construction, shall be of such a nature as to reduce the likelihood of injury to the contents of the bag or danger of bystanders being struck by the bag.

These objects and other advantageous ends I secure as hereinafter set forth, reference being had to the accompanying drawings, in which,

Figure 1 is a perspective view of a portion of a car showing the bag supporting and collecting device constituting a part of my invention, with the device for receiving a bag from said car and the bag supporting structure for delivering a second bag to a device on the car;

Fig. 2 is a vertical section illustrating certain of the detail features of part of my invention;

Figs. 3 and 4 are respectively front and

side elevations of the connection between one of the bag supporting arms and the pivot bar;

Figs. 5 and 6 are respectively a side and a front elevation of one of the bag retaining clips;

Figs. 7 and 8 are respectively a plan and an elevation both partly in section, illustrating a modification of my invention; and

Fig. 9 is a perspective of the supporting bracket of Figs. 7 and 8.

In the above drawings 1 represents a portion of one side of a mail car having a doorway 2, on the vertical edges of which are fastened a pair of bearing brackets 3 and 4 in which is rotatably mounted a horizontally extending pivot bar 5 preferably of the construction commonly in use. Rigidly attached to this pivot bar by any suitable means, is a sleeve 6 having a projecting handle 7 opposite which it has fixed to it a bag catching arm 8. This arm is preferably bent to the rear a short distance from the sleeve to provide a bag catching hook or recess 9 and in the present instance its outer end is provided with a rearwardly projecting bag holding clip 10.

Also fixed to the bar 5 is a second sleeve 12 from which an arm 11 extends downwardly and outwardly, there being another bag holding clip 13 on its extremity which is so situated that a mail bag α may be suspended between this and the clip 10, in a more or less tensed condition. In the present instance I have shown the arm as held in the sleeve 12 by a set screw which may be actuated by hand, although obviously any other means for coupling these parts may be provided without departing from my invention.

At each of the various points at which mail bags are to be delivered along the railroad whose mail cars are equipped with the apparatus just described, I erect a suitable post or standard 14 and attach to its upper part a bag-receiving arm 15 by means of a horizontally extending pivot bolt 16. The arm is normally held in a substantially vertical position by means of a weight 17 fixed to its lower end and its portion above the pivot is connected to one side of a rearwardly opening, U-shaped bag catcher or receiver 18. Obviously the post 14 is mounted at such a distance from the path of a mail bag α carried by the arms 8 and 11

when these are properly extended, that said bag will enter the receiver 18, which lies in a horizontal plane passing through or immediately adjacent the center of said bag, 5 and in order to insure the retention of the latter I preferably provide said receiver or catcher with retaining springs 19, each of which has one end connected to the extremity of one of the branches of the fork 10 while the other end terminates adjacent its bottom or most forward portion. This spring is preferably so bent as to provide a rounded edge, narrow, tapering but relatively yielding throat through which a bag 15 is guided into the forward larger portion of the catcher, and in which such bag is effectually held from rebound or accidental dislodgement.

A stationary bag holding post 20 of the 20 ordinary type or of any other suitable construction may also be mounted adjacent the path of the moving car and be provided with projecting arms 21 and 22 whereby a bag to be taken into the car is suspended in 25 a substantially vertical position so that it will be engaged by the U-shaped portion 9 of the arm 8 when this latter is turned into a horizontal plane outside of the car.

When it is desired to mount a mail bag 30 on the arms 8 and 11 ready for delivery, the latter, by means of the handle 7, are swung into the position shown in dotted lines in Fig. 2 so that they extend within the car, at about the height of the operator's 35 shoulder. In this position a mail bag may be readily mounted on the clips 10 and 13 so as to be held between them in the desired position, after which, as the car approaches a mail receiving station, said arms with the 40 bag are swung down and outwardly into the positions shown in Fig. 1. In order to limit their movement and prevent the possibility of their being raised above the desired height outside of the car, I preferably 45 mount on the pivot bar 5 a relatively stout projecting pin or stop 23 and so form one end of the bearing bracket 4 that it provides a shoulder 24 placed to be engaged by said stop when the arms have been swung 50 up outside of the car into the positions necessary to bring the mail bag into the line of the jaws of the catcher 18. Even though the car be moving at a high rate of speed, the bag, after being guided into said catcher 55 is drawn out of engagement with the clips 10 and 13 of the arms 8 and 11 and the energy of its movement is absorbed by the weight so that the arm 15 is turned on its pivot through a greater or less angle after 60 receiving said bag and may be even caused to rotate. If a second bag α' is to be taken in by the car, the arms are held by the operator in their extended or raised positions so that such bag, held by the arms 21 and 65 22, enters the receiving portion 9 of the arm

8, from which it is removed in the customary manner.

When not in use the arms 8 and 11 are allowed to swing down and if desired the latter arm, which would extend into the car, 70 may be removed. The movable door 25 may if desired be provided with a slot 26 (Fig. 1) designed to receive the projecting portion 12 to which the arm 11 is connected, in order that said door may be closed when the device is not in use.

From the above description it will be noted that my invention may be applied to the well known mail bag-receiving apparatus commonly in use with but little 80 modification of its present construction, while the stationary structures designed to receive mail bags are of substantial, simple and yet inexpensive design, easily installed and maintained in operative condition.

In that form of my invention shown in Figs. 7 to 9 inclusive I mount the structure for suspending a mail bag beyond the side of a moving car, upon a bracket 30 fixed to one of the door jambs preferably in such position as not to interfere with the ordinary working of the door. This bracket is formed with a vertical pivot 35 for a second bracket 30^a and this in turn has an outwardly extending horizontal pivot 31 perforated adjacent its end for the reception of a cotter pin 32 whereby a bag-supporting structure is removably held in position while being free to oscillate on said pivot as a horizontal axis.

The bag holding structure which is rotatably mounted on the pivot 31 consists of an upper arm 8^a provided with a curved bag-receiving portion 9^a as well as with a suitable clip 10 for engaging one end of a mail bag or pouch. Said portion 9^a is formed with a spring retaining member 50 which like the springs 19 presents a curved edge to a bag to be engaged so as to avoid danger of cutting the same. In the present 110 instance formed integral with the arm 8^a, is a downwardly extending portion 33 from which projects a second arm 11^a lying in a plane substantially parallel to that of the outer part of the arm 8^a and like it provided at its outer end with a bag engaging clip 13. The member 33 is extended downwardly below the point of attachment of the arm 11^a and terminates in a weight 34 which when the bag is suspended ready for delivery, hangs adjacent the door jamb 1^a on which the bracket 30 is mounted.

This bracket 30, in addition to the pivot bracket 30^a has a cylindrically curved recess 40 designed to engage the correspondingly curved surface of the hub 38 which fits on the spindle 31. A braking lever 37 also pivoted to the bracket 30^a has a concave end likewise formed to coact with the hub 38 and it includes a rearwardly extending arm 130

- 41 designed to coat with a lug 39 on the bracket 30^a, so that this with the structure 55
8^a—33—11^a may be swung on the pivot 35 into the car.
- 5 Under conditions of use a mail bag α is mounted upon the arms 8^a and 11^a within the car and thereafter the structure as a whole with said bag is swung outwardly upon the pivot 35 into the position shown in 60
10 Fig. 8. The mail bag may then be delivered to the stationary receiving apparatus along the track as previously described.
- When it is desired to collect a mail bag from a suspending device along the track, 15 the operator exerts an outward pressure upon the handle or lever 36 so that the energy developed by the stationary bag striking the rapidly moving arm structure 8^a is absorbed partly in turning the structure 20 8^a—33 and 11^a with the weight 34 upon the pivot 31, and partly by the friction or braking action of the arm 37 on the hub 38.
- I claim:
1. A mail bag receiving device consisting of a supporting structure including a horizontal pivot; a bag catching arm mounted to turn on said pivot; with a weight on the arm normally holding it in a substantially vertical position with its hook in a horizontal plane.
  2. A mail bag receiving device consisting of a supporting structure including a horizontal pivot; a substantially U-shaped bag engaging member carried by said arm; and a weight normally retaining said arm with the member in a bag receiving position and opposing movement of the arm under the action of a bag.
  3. The combination of a supporting structure; an arm mounted thereon and free to turn on a substantially horizontal axis; a substantially U-shaped bag receiving member carried by the arm; and a depending weight normally retaining said arm in an elevated position with the bag receiving member in a substantially horizontal plane ready to receive a bag.
  4. The combination of a supporting structure; an arm mounted thereon and free to turn on a substantially horizontal axis; a substantially U-shaped bag receiving member carried by the arm; with a weight normally retaining said member in a substantially horizontal plane ready to receive a
- bag and acting to oppose movement of the arm and bag receiving member.
5. The combination of a supporting structure; a bearing thereon; a spindle carried by said bearing so as to extend in a horizontal line; an arm extending downwardly from said spindle; a weight on the lower end of said arm; a branch arm projecting from said arm; a second arm extending upwardly from the spindle and thereafter projected outwardly for a distance substantially the same as that of the branch arm; with mail bag supporting devices carried by said two latter arms.
6. The combination of a supporting structure; a horizontal spindle mounted thereon; an arm extending upwardly from said spindle and then projected outwardly; a substantially U-shaped bag catching structure having one of its sides connected to said arm and its other side projected outwardly; a second arm extending down from said spindle and having a branch projecting for substantially the same distance as the outer member of the bag catching structure; with a weight tending to retain said arms in a position one over the other.
7. The combination of a supporting structure; a vertical pivot carried thereby; a bracket rotatably mounted on said pivot and including a horizontal spindle; a hub mounted on the spindle; a downwardly extending laterally projected arm on said hub; a weight on the lower portion of said arm; and an arm extending upwardly from the hub and having a laterally projecting portion formed to coöperate with the projecting portion of the first arm to support a mail bag.
8. The combination of a supporting structure; a vertical pivot carried thereby; a bracket rotatably mounted on said pivot and including a horizontal spindle; a hub mounted on the spindle; a downwardly extending laterally projected arm on said hub; a weight on the lower portion of said arm; an arm extending upwardly from the hub and having a laterally projecting portion formed to coöperate with the projecting portion of the first arm to support a mail bag; with a brake operative on the hub to retard rotation thereof on the spindle.

WILLIAM J. RHOADS.
